UNITED STATES PATENT OFFICE

BENJAMIN FRANKLIN TRUESDELL, OF COLLINGWOOD, ONTARIO, CANADA

OIL BURNER

Application filed September 26, 1927. Serial No. 222,918.

This invention relates to an oil burner for use in the heating of dwellings, stores and similar buildings, and which is installed in an ordinary coal furnace or heater, generally by placing the apparatus in the ashpit of the furnace.

My object is to devise apparatus of this type by means of which improved combustion and therefore greater heating effect is obtained for the amount of oil consumed.

I attain my object by providing improved means for preheating the air supplied to the nozzle and by providing means for obtaining a more thorough breaking up of the oil 15 and admixture of air therewith at the nozzle.

The improved apparatus is constructed substantially as hereinafter more specifically described and illustrated in the accompanying drawings in which

20 Fig. 1 is a plan view of my improved apparatus;

Fig. 2 a side elevation of the same;

Fig. 3 a vertical section through the burner mechanism;

25 Fig. 4 a vertical section on the line 4—4 in Fig. 1;

Fig. 5 a detail illustrating the hollow motor shaft with the nozzle attached thereto,

And Fig. 6 is a section through the nozzle.

30 In the drawings like numerals of reference indicate corresponding parts in the different figures.

My apparatus comprises a hollow body 1, U-shaped in plan. A partition 2 is formed 35 within the hollow body in substantial alignment with the inner wall of one leg, thereby dividing the interior of the body into two passages 6 and 7. The end of each leg of the body has an opening 3 in its upper surface,

40 said openings being connected by means of a hollow member 4, on the side of which is located a flame spreader 5. The passage 6 opens at 27 through the outer wall of the body at the bottom of the U and the passage 7 opens 45 at 28^a (see Figs. 3 and 4) through the inner wall of the body at the bottom of the U.

Supported on the hollow body is the nozzle 8, which is hollow and has an opening 28 in its rear side near the bottom communicating 50 with the opening 28^a to the passage 7 in

the body, and also an opening 29 in its rear side near the top communicating with a hollow member 9 supported on the body. The forward wall 30 of the nozzle is preferably concaved or cup shaped as shown. The hollow member is formed of two parts bolted together, the upper part 9^a having a hole 29^a in its side in alignment with the upper hole 29 in the rear of the nozzle 8 and the lower part a discharge outlet 31 in alignment with an opening 32 formed centrally of the nozzle.

Air entering the open end of the passage 6, it will be seen, passes along said passage, through the hollow member 4, then through the passage 7, into the hollow nozzle 8, 65 through the parts of the hollow member 9, and is discharged through the central hole in the nozzle.

For supplying air to the passage 6, a fan 10 is provided located in a housing 11. The 70 housing is spaced from the hollow body 1 by means of an air intake casing 12, preferably formed of a number of sections 33, 34, 35 bolted together and provided with air inlet openings 13 in its top and sides and an outlet 36 arranged axially of the fan 10.

The fan is mounted on the shaft 14 of the electric motor 15. For a purpose which will shortly appear the motor shaft is hollow and is of a length sufficient to extend beyond the fan 10, and has a tubular sprayer 16 mounted thereon. The sprayer gradually increases its diameter towards its outer end, and is preferably removable so that sprayers of larger or smaller internal diameter may be substituted. 80 In the drawing the sprayer is shown as threaded on the end of the shaft. The sprayer is preferably provided with fins 37 on its outer surface adjacent its discharge end.

17 is an oil supply pipe, which will in practice be connected with a suitable oil supply tank, and leads to an oil dropper 18, which dropper is connected with a pipe 19 leading through the hollow shaft 14 and discharging into the sprayer 16. The oil dropper is preferably provided with a glass portion 38 so that it may be seen whether or not the oil is being properly fed.

A needle valve 20 is provided to regulate the flow of oil to the dropper and a pivoted 100

gate 21 is provided for controlling the flow of air through the outlet of the fan housing. For simultaneously actuating the needle valve and the gate, the stem 22 of the needle valve is extended and is provided with a wheel 23 thereon by means of which it may be rotated. On the stem is secured the crank arm 24 which is connected by means of a link 25 with an arm 26 connected with the gate 21. It will thus be seen that by rotating the wheel 23, both the gate and valve may be simultaneously opened or simultaneously closed.

The operation of the apparatus is as follows. Oil is fed to the supply pipe 17 and at the same time the motor 15 is set in operation to operate the fan 10 and rotate the sprayer 16. As the oil enters the sprayer 16, owing to the larger diameter of the latter and its rapid rotation, the oil is spread out into a very thin sheet and broken up as it travels outwardly in the sprayer for discharge into the nozzle 8. At the same time air forced through the passages 6, 4, 7, 28, 29 and 32 by the fan 10 is discharged through the centre of the nozzle and mixes with the oil, and it is found that the provision of the fins 37 on the end of the sprayer 16 avoids to a large extent the danger of a greater quantity of air being supplied at one side of the sprayer than the other.

Preferably the nozzle will have a concavo-convex reinforcing plate 39 therein, and I may also form independent passages 27 through the nozzle so that a certain amount of fresh air may be mixed with the preheated air in the nozzle. This fresh air is taken from the air chamber 12, and passes through a pipe 40 into the space 41 in the member 9, thence into the annular cavity 42 in the nozzle 8.

I show the nozzle and the hollow member 9 as formed of three separate parts, but it will be evident, of course, that they may be made as an integral casting if desired.

From the construction described it will be seen that the air for mixture with the oil is preheated to a high temperature during its passage through the apparatus prior to discharge into the firepot. It will also be seen that by interposing the air inlet casing between the combustion chamber of the furnace and the fan and motor, overheating of the latter is avoided. The providing of the motor with the hollow shaft through which the oil is fed provides a very convenient method of breaking up the oil for mixture with the air at the point of combustion.

What I claim as my invention is:

1. In an oil burner, the combination of a body having an air preheating passage therethrough; a nozzle having an air supply opening therethrough communicating with one end of said passage; a motor having a hollow shaft forming an oil supply nozzle adapted

to discharge through said opening; a fan on said hollow motor shaft; a housing enclosing said fan and having a discharge opening communicating with the air preheating passage; and an air intake casing communicating with the fan housing and interposed between the fan housing and the body.

2. In an oil burner, the combination of a body having an air preheating passage therethrough; a nozzle having an air supply opening therethrough communicating with one end of said passage; a motor having a hollow shaft forming an oil supply nozzle adapted to discharge through said opening; a fan on said hollow motor shaft; a housing enclosing said fan and having a discharge opening communicating with the air preheating passage; and an air intake casing communicating with the fan housing and interposed between the fan housing and the body, an air preheating portion of said body extending in front of the nozzle and forming a spreader against which the flame from the nozzle may impinge.

Signed at Collingwood, this 22d day of August, 1927.

BENJAMIN FRANKLIN TRUESDELL.
